UNITED STATES PATENT OFFICE.

WILLIAM E. ALLINGTON, OF SAGINAW, MICHIGAN.

FAN-BLOWER HEATING APPARATUS.

SPECIFICATION forming part of Letters Patent No. 623,848, dated April 18, 1899.

Application filed February 6, 1899. Serial No. 704,701. (No model.)

To all whom it may concern:

Be it known that I, WILLIAM E. ALLINGTON, of Saginaw, East Side, in the county of Saginaw and State of Michigan, have invented 5 certain new and useful Improvements in Fan-Blower Heating Apparatus, of which the following is a specification.

This invention relates to fan-blower heating apparatus, or, in other words, to that class 10 of heating and ventilating apparatus in which rotary fans are employed for the purpose of inducing and delivering the air-currents to be heated. Heretofore in practice it has been customary to construct a separate heater of 15 steam-pipes and to inclose said steam-pipes in a suitable casing, with which casing a rotary fan-blower is connected for the purpose of either drawing or blowing the air-currents over the pipes in the heater-case in one direction with relation to said pipes—that is to say, either transversely or longitudinally thereof. With this construction only about 20 one-half of the entire heating-surface of the pipes is effective in heating the air-currents—to wit, that portion of the heating-surface which is presented toward the incoming air-currents. It is therefore with this construction necessary to furnish a heater with nearly 25 double the actual heating-surface which would be required to do the work in the case of a heater so constructed as to cause the air-currents to come into contact with the entire surface of the pipes. Moreover, the space occupied by an apparatus constructed on this 30 plan with the fan and heater separated, but joined by a suitable duct or conduit through which the air is delivered from the fan to the heater, often makes it difficult to find sufficient room for installation. Moreover, in 35 heaters of this type the circulation of the steam is imperfect, and they are also subject to air binding within the pipes, these causes producing further loss of efficiency, while in some of the forms in common use the least effi- 40 cient parts of the heater are the most expensive to manufacture. It has also been proposed to inclose the fan in a casing having a single tangential outlet in its peripheral portion, the casing being of greater diameter than the 45 fan and the heating-pipes occupying the space thus formed between the fan and the periphery of the casing. This construction is also

open to the objection that only a portion of the heating-surface of the pipes is exposed to the air-currents except at the point of discharge, so that full efficiency of the heating-surface provided by said pipes is not effectively utilized.

It is the object of my invention to overcome the objections just pointed out and to 60 provide an apparatus compact and self-contained occupying little or no more space than has been occupied heretofore by either the fan alone or the heater alone and comprising a complete device including fan, heater, coils, 65 and manifolds, the parts of which are so arranged and disposed with reference to each other as to give full effect to all of the heating-surface employed, certain and positive circulation of the steam through the pipes 70 constituting the heating-surface, high efficiency in delivering the air-currents from the fan through the air-spaces between the heating-pipes, economy in space occupied, as well as in the material and labor which go to make 75 up the cost of construction, and in which provision is made whereby regulation of the heater may be readily effected.

To these ends my invention consists, primarily, in a fan-blower heating apparatus 80 comprising a rotary fan-wheel, a plurality of heating-pipes surrounding said fan-wheel, feeding and drip manifolds, to the ends of which said pipes are respectively connected, and a casing for said wheel and pipes having 85 a substantially continuous lateral outlet at the margin of one of its sides, whereby the air is forced from all points on the periphery of the fan to travel in a continuous current radially outward between the heater-pipes 90 and also lengthwise of these pipes, and also and at the same time laterally outward between the pipes in a direction parallel with the axis of the fan, being discharged from the heater through an opening or openings ex- 95 tending over a large area.

The invention also consists in certain other novel features, which will be hereinafter more particularly described, and then pointed out in the claims.

In the accompanying drawings, Figure 1 is a side elevation, partly in section, of an apparatus embodying my invention in its preferred or most highly-developed form. Fig.

2 is a vertical sectional view of the same. Fig. 3 is a view, similar to Fig. 1, illustrating a modified form of the apparatus shown in Figs. 1 and 2, in which the heater is composed of straight pieces. Fig. 4 is a vertical sectional view of the same. Fig. 5 is a plan view of a modification of the apparatus shown in Figs. 3 and 4, adapted for use in spaces of contracted height and with the fan and heating-pipes arranged in an approximately horizontal position. Fig. 6 is a sectional view of the same, taken on the line 6 6 of Fig. 5. Fig. 7 is an enlarged detail plan view of one of the corners of the apparatus shown in Figs. 5 and 6. Fig. 8 is a sectional view of the same, taken on the line 8 8 of Fig. 7 and looking in the direction of the arrow. Fig. 9 is a sectional view taken on the line 9 9 of Fig. 7 and looking in the direction of the arrow. Fig. 10 is a view of a further modification of the apparatus, embodying the employment of a plurality of fans, the heater being constructed in the manner shown in Figs. 4 and 5. Fig. 11 is a view illustrating a further modification of the apparatus analogous to that form shown in Figs. 3 and 4 and illustrating the adaptation of my invention to a type of heater now in common use. Fig. 12 is a vertical sectional view of the apparatus shown in Fig. 11. Fig. 13 is an enlarged detail view of that portion of the upper manifold and its associated parts shown in section in Fig. 1, and Fig. 14 is a similar view of the lower manifold shown in section in said figure.

35 Referring first to the preferred form of my apparatus shown in Figs. 1 and 2 of the drawings, 15 indicates a supporting-frame on which the apparatus is mounted and which is provided with annular portions 16 on each side 40 of the apparatus, having bearings 17, in which is mounted the shaft 18 of the fan 19. The fan may be driven in any suitable manner, and in Fig. 2 of the drawings I have shown the fan-shaft as coupled directly to the main shaft of an engine 20, which is mounted on a pedestal or bracket 21 at one side of the apparatus. The fan is surrounded by a plurality of pipes 22, which form the heater and which in the preferred form shown in Figs. 1 45 and 2 are circular in their general arrangement, being substantially concentric with the axis of the fan and forming an annular body, surrounding the same with the innermost pipes in immediate proximity to the outer edges of the fan-blades. In the construction shown these pipes 22, which constitute the units of the heater, are each approximately semicircular in form and have their upper ends connected to a supply or feeding manifold 23 and their lower ends to a drip-manifold 24. I prefer to divide the manifolds into sections, as shown, and in the particular construction shown the upper or feeding manifold comprises three sections, each adapted 55 to receive the ends of two transverse rows of pipes on each side, while the lower or drip manifold comprises six sections, each adapted

to receive the ends of a single transverse row of pipes on each side. The particular subdivision of the manifolds hereinbefore described is that which I prefer for the reasons hereinafter given; but I do not wish to be understood as limiting my invention thereto. The sections of the manifolds are separated by air-spaces 25 to prevent the interruption of the passage of air-currents longitudinally of the pipes, and to facilitate the proper spacing of the sections they are provided with projections or lugs 26 on their under side which rest upon the tops of the subjacent sections. 70 The manifolds are supported by brackets 27, extending upward from the supporting-frame 15. The upper or feeding manifold-sections are preferably supplied with steam at their ends, and each section is independently supplied. In the construction shown each section is connected at one end with a pipe 28, having a controlling-valve 29, and said pipes 28 are in turn connected with a supply of exhaust-steam to adapt the heater for use where 75 such exhaust-steam is to be employed as the heating fluid. At their other ends said sections are each provided with a pipe 30, having a controlling-valve 31, said pipes being connected with a source of supply of live steam, so that the live-steam supply may be drawn upon for heating purposes. With this construction it is desirable to employ a reducing-valve between the heater and the live-steam supply in order to permit the conjoint use of the live-steam and exhaust-steam. The sections of the drip-manifold are each provided with a discharge-pipe 32, having a controlling-valve 33, and also at the other end each of said sections is provided with an air-valve 34.

80 The arrangement of the pipes which I prefer is that known as a "staggered" arrangement, in which the pipes of one transverse series lie radially opposite the spaces between the pipes of the adjacent series, as shown in the drawings.

85 The fan and heater are inclosed in a suitable casing, and in its preferred form this casing consists of side pieces 35 and a peripheral portion 36. The side pieces are annular in form, having a central opening 37, through which air is admitted to the interior of the casing, and said side pieces are of less diameter than the heater proper and the inclosing peripheral portion 36 of the casing, whereby there is formed on each side of the apparatus a space or opening 38 between the outer margin of the side piece and the edge of the peripheral portion of the casing, which 90 spaces or openings are preferably substantially continuous, as shown, and which are located at the outer margins of the sides of the casing. These openings form the outlets through which the heated air is discharged 95 from the apparatus, and in the particular form shown there are two of these outlets, one at each side of the apparatus; but it is obvious that if the requirements of the case

call for an apparatus discharging heated air on one side only one of said discharge openings or outlets may be closed by making the lateral portion of the casing on that side continuous from the receiving opening or inlet 5 to the margin of the peripheral portion 36 of the casing.

The ends of the semicircular pipes 22 may be connected to the manifolds in any suitable 10 manner; but I prefer for this purpose the construction shown more particularly in Figs. 1, 13, and 14 of the drawings, in which there is provided a plurality of right and left threaded 15 coupling-sections 39, having a central wrench-grasp 40, by means of which they can be rotated and screwed into correspondingly-threaded apertures in the ends of the pipes 22 and in the manifolds, respectively. By 20 these means each semicircular pipe 22 may be readily connected at its ends to the two manifolds, and by reason of this construction, the coupling-sections being of less internal 25 diameter than the pipes, the steam passage or conduit is reduced at the point where steam is admitted to the pipe-sections, and by reason 30 of the reduction at this point I have found that in practice a more efficient and even distribution of the heating effect of the steam may be obtained.

The apparatus thus constructed is particularly adapted for the heating of large spaces which are not subdivided—as, for example, large rooms unobstructed by partitions. In the operation of the apparatus the air is blown 35 by the fan radially across the pipes in a direction outward from the axis of the wheel by reason of the centrifugal force developed by the rotation of the fan-wheel. The air is also caused to move lengthwise of the pipes by 40 reason of the angular velocity imparted to it by the fan-wheel. Finally, the air, being unable to escape in either of the directions indicated by reason of the presence of the peripheral portion 36 of the casing, is caused to move 45 laterally in a direction parallel with the axis of the fan-wheel shaft in order that it may escape through the lateral opening or openings provided for that purpose. It will of course be understood that during this movement of the air in these several directions it 50 is brought thoroughly into contact with all sides of the heating-pipes and with all portions thereof, so that the heating-surface of the heater is thoroughly utilized. It therefore follows that by the use of this apparatus I am enabled to dispense with a considerable amount of pipe, as compared with such heaters as ordinarily constructed, without any diminution in the heating effect, or, in other 55 words, a smaller total amount of piping will produce the same heating effect or the same amount a greater effect. The advantages due to the reduction in the amount of space occupied, superior compactness, and the self-contained nature of the structure will also be at 60 once apparent. The subdivision of the manifolds into sections having air spaces or pas-

sages between them prevents any interruption in the continuity of the travel of the air-currents longitudinally of the heater-pipes 70 and at the same time presents a large increased heating-surface.

The heating effect may be controlled in various ways—as, for example, by regulating the admission of steam by means of the valves 75 29 or 31, or both of them, and these valves may also be so manipulated as to admit steam to some of the groups or sections of pipes, while excluding it from others. I prefer, however, to regulate the heating effect by manipulating the valves of the sections of the drip-manifold, and this may be done either by closing one or more of the drip-valves 33, according to the number of pipes which it is desired to cut off or render non-effective, where- 80 upon the drip-manifold section or sections and the pipes connected therewith, of which the drip valve or valves have been closed, will become filled with water, and thereby rendered non-effective as heating devices. If 85 desired, however, the same end may be obtained by opening one or more of the air-valves 34 while the proper steam-valves are turned off, and thus permitting any desired portion of the heater to fill with air and become dead. I prefer the subdivision of the drip-manifold into a large number of sections, for the reason that a finer regulation of the 90 heating effect may thus be obtained, and in the construction shown any one or more of the rows of pipes may be cut out, if desired. I have found, however, that it is not desirable to so minutely subdivide the feeding-manifold, as the proper supply of steam to the 95 pipes would be thereby interfered with. 100

It is obvious, of course, that the heating effect may also be regulated by controlling the velocity of the fan.

The construction just described is, as already stated, that which I deem the most 110 highly-developed form of my invention and which I prefer under ordinary circumstances. The circular form of the heating-pipes enables me to bring them into close proximity to the line of travel of the edges of the fan-blades, and thereby renders the contact between the air and said pipes, due to the angular velocity imparted to the air by the fan, more complete and effective. I do not, however, wish to be understood as limiting my invention to an apparatus in which the heating-pipes are circular in form, and in Figs. 3 and 4 I have shown an apparatus in which the heater is constructed of straight pipe-sections and is rectangular in its general form. 115 In this construction the straight sections of pipe 41 are connected at their ends by angle-fittings 42 at two of the corners of the apparatus, while the feeding-manifold 23 and drip-manifold 24 are located at the other two corners of the apparatus. The upper and lower rows of pipes are preferably not exactly horizontal, but are inclined, as shown, the upright pipes being similarly inclined to pre- 120 125 130

serve the rectangular form of the heater and this inclination serving to effectively drain the heating-pipes and prevent the accumulation of water therein and at the same time 5 assist the circulation of the steam. With this construction the pipes 41 may be screwed directly into the manifolds without the intervention of intermediate coupling-sections.

In the forms of apparatus hereinbefore described the arrangement thereof is one which might be termed "vertical," the fan rotating in a vertical plane around a horizontal axis and the heater and its case standing at a considerable height. My invention is not, however, limited to a construction wherein this vertical arrangement of the apparatus is followed, and in Figs. 5 to 9 of the drawings, inclusive, I have shown a form of apparatus which may be termed a "horizontal" apparatus, in which the fan revolves around an axis which more nearly approaches the vertical than the horizontal, so that the plane of revolution of the fan is approximately horizontal and the pipes are arranged in corresponding planes. This form of apparatus is particularly adapted for use in localities where the vertical height available is restricted and where an upright apparatus of sufficient size to provide proper heating capacity 30 could not be used. I have also in this connection shown the heater as so constructed as to be divided in a vertical plane into two parts or groups, each composed of a plurality of separable sections, so that this particular 35 style of apparatus is particularly adapted for large installations where the parts are necessarily too heavy to be shipped or handled after the apparatus is assembled. Referring more particularly to the construction under 40 consideration, the feeding-manifold 23 is composed of a plurality of sections superposed upon each other in two separate vertical series, with intervening air-spaces 25 between the sections and each section being provided 45 with a separate steam-supply pipe 28 in the manner hereinbefore described. The pipes 41 are straight, as in the construction already described in referring to Figs. 3 and 4, and are joined by angle-fittings 42, and the rows of 50 pipes connected to one section of the feeding-manifold are connected at their other ends to the corresponding section of the drip-manifold 24, which is constructed of sections divided horizontally and vertically in the same manner as the feeding-manifold. The result of 55 this construction is that the heater as a whole is composed of separate sections, each comprising one or more rows of pipes, two being shown in the present instance, one-half of a 60 horizontal section of the feeding-manifold and one-half of a horizontal section of the drip-manifold. These units of construction may be readily transported and handled, and the heater may be constructed or built up of 65 them by simply superposing them one upon the other in two series properly arranged relatively to each other, so as to inclose the fan.

The detailed construction of the manifold-sections which I prefer to employ in this structure is shown more particularly in Figs. 7c 7, 8, and 9, the sections being each provided with a plurality of shoulders or offsets 43 to receive the ends of the pipes 41, said shoulders or offsets being stepped, as shown, and in the case where each section receives two 75 rows of pipes the stepped offsets are also staggered or alternately arranged, as shown more particularly in Fig. 8.

In Fig. 10 of the drawings I have shown another modified form of my invention, which 80 is also adapted for use where the available space is so contracted vertically that a rectangular or circular heater, such as those hereinbefore described, will not provide sufficient heating capacity to meet the requirements of the case when vertically arranged, and it is not desired to use the horizontal form just described. In this construction the upper and lower rows of pipes of the heater are made longer than those at the ends, so 90 that the entire heater is given an elongated shape, and a plurality of fans are placed in the elongated space thus provided within the heater. In the present instance I have shown two of these fans, located, respectively, at 95 each end of the elongated space thus formed, there being provided between the fans, if desired, an air-space 44, which is partially cut off from the fan-spaces by partitions 45, so arranged as to leave communicating openings 46. This air-chamber may be provided 100 with a damper 47 in one or both sides of the casing, and, if desired, a delivery of cold air may be made through these dampers for the purpose of effectually increasing the volume 105 of air delivered from the apparatus and at the same time reducing its temperature.

In Figs. 11 and 12 I have shown a very simple form of my apparatus which is adapted 110 for application to a type of heater already in general use and which is characterized by the employment of manifolds at the bottom of the heater, with a plurality of pipes rising vertically thereof and connected in pairs by a corresponding plurality of horizontal pipes at 115 their tops. In this construction, the pipes being nested within the other, the innermost pipes being shorter, and consequently smaller, are least efficient in proportion to their cost, since the expense of threading and joining 120 them is as great as that of threading and joining the outer and longer pipes, which present more heating-surface, while owing to their short length it is much more difficult to assemble them. In the construction which I have 125 devised these central or innermost heating-pipes are dispensed with and the fan is placed in the opening or space thus formed in the interior of the heater and inclosed by side plates 35 of a proper shape to close the said 130 opening at the sides thereof. In this construction I arrange a feeding-manifold 23 and a drip-manifold 24 on each side of the apparatus, so as to equalize the heating on both

sides of the heater and obviate the objection heretofore existing in such heaters as usually constructed, wherein all the ascending pipes on one side receive the hottest steam and all 5 the descending pipes on the other side receive only the water of condensation and that part of the steam not already condensed, but already low in temperature, so that the heating-surface is effectual on one side of the apparatus only. In this construction the space 10 below the fan-wheel is not occupied by pipes or heating-surfaces of any kind, and a damper 48 is provided in one or both sides of the apparatus, which may be utilized in the manner 15 already indicated in referring to the construction shown in Fig. 10.

It is obvious that modifications of the structures hereinbefore set forth may be made without departing from the principle of my invention. It will be observed that in each of the 20 several structures hereinbefore described and shown in the drawings there is present a rotary fan-wheel, a plurality of heating-pipes surrounding said fan-wheel, feeding and drip 25 manifolds to which the ends of said pipes are respectively connected, and a casing for said wheel, and pipes which inclose them peripherally and laterally except for the inlet-openings at the centers of the lateral portions of 30 the casing and for the outlet-openings, which are substantially continuous and which are located at the margins of the sides of the casing, so that in each instance the currents of air produced by the fan have the several motions hereinbefore described and impinge 35 upon all portions of the heating-surfaces presented by the pipes of the heater. I regard any structure which comprises these features, either in the form just stated or in the modified form wherein one of the discharge-outlets is closed, as being within the scope of my 40 invention, and I therefore do not wish to be understood as limiting myself to the precise details hereinbefore described and shown in 45 the drawings.

I claim—

1. In a fan-blower heating apparatus, a rotary fan-wheel, a plurality of heating-pipes surrounding said fan-wheel, feeding and drip 50 manifolds to which the ends of said pipes are respectively connected, and a casing for said wheel and pipes having a substantially continuous lateral outlet at the margin of one of its sides, substantially as described.
2. In a fan-blower heating apparatus, a rotary fan-wheel, a plurality of heating-pipes surrounding said fan-wheel, feeding and drip 55 manifolds to which the ends of said pipes are respectively connected, and a casing for said wheel and pipes having substantially continuous lateral outlets at the margins of its sides, substantially as described.

3. In a fan-blower heating apparatus, a rotary fan-wheel, a plurality of heating-pipes arranged in close proximity to the periphery 65 of the said fan-wheel and substantially concentric with the shaft thereof, feeding and drip manifolds to which the ends of said pipes are respectively connected, and a casing for said wheel and pipes having a substantially continuous lateral outlet at the margin of one of its sides, substantially as described.

4. In a fan-blower heating apparatus, a rotary fan-wheel, a plurality of heating-pipes surrounding said fan-wheel, feeding and drip 75 manifolds to which the ends of said pipes are respectively connected, said manifolds being each divided into sections having air-passages between them, and a casing for said wheel, pipes and manifolds having a substantially 80 continuous lateral outlet at the margin of one of its sides, substantially as described.

5. In a fan-blower heating apparatus, a rotary fan-wheel, a plurality of heating-pipes surrounding said fan-wheel, feeding and drip 85 manifolds to which the ends of said pipes are respectively connected, the manifolds being divided into sections and the pipes connected thereto in groups or series, means for independently controlling the passage of the heating 90 fluid through said groups or sections, and a casing surrounding said wheel and pipes and having a substantially continuous lateral outlet at the margin of one of its sides, substantially as described. 95

6. In a fan-blower heating apparatus, a rotary fan-wheel, a plurality of heating-pipes surrounding said fan-wheel, feeding and drip manifolds to which the ends of said pipes are respectively connected, said pipes being of reduced internal diameter at their point of connection with the feeding-manifold, and a casing for said wheel and pipes having a substantially continuous lateral outlet at the margin of one of its sides, substantially as described. 100 105

7. In a fan-blower heating apparatus, a rotary fan-wheel, a plurality of semicircular pipes surrounding said fan-wheel and arranged in two groups on opposite sides thereof, feeding and drip manifolds located between the ends of the groups, right and left threaded coupling-sections connecting each end of each semicircular pipe with the adjacent manifold, said pipes and manifolds being provided with reversely-threaded apertures 110 115 to receive the ends of said coupling-sections, and a suitable casing surrounding said fan-wheel, pipes and manifolds, substantially as described.

WILLIAM E. ALLINGTON.
